UNITED STATES PATENT OFFICE.

ARTHUR H. POHL, OF CHICAGO, ILLINOIS.

APPARATUS FOR THE TREATMENT OF CERTAIN DISEASES.

SPECIFICATION forming part of Letters Patent No. 788,943, dated May 2, 1905.

Application filed October 31, 1904. Serial No. 230,697.

To all whom it may concern:

Be it known that I, ARTHUR H. POHL, a subject of the Emperor of Germany, residing at Chicago, in the county of Cook and State of Illinois, have invented certain new and useful Improvements in Apparatus for the Treatment of Certain Diseases, of which the following is a specification.

My invention relates to certain new and useful improvements in apparatus for the treatment of certain diseases; and its object is to produce a device of this class which shall have certain advantages which will appear more fully and at large in the course of this specification.

To this end my invention consists in certain novel features which are fully illustrated in the accompanying drawings and described herein.

In the aforesaid drawings, Figure 1 is a longitudinal section through my improved device. Fig. 2 is a plan view of the rheostats and the ring which supports them. Fig. 3 is a bottom plan of the device with the hood and reflector removed. Fig. 4 is an under plan of the upper glower-support and the glowers supported thereby. Fig. 5 is an enlarged fragmental view similar to Fig. 1. Fig. 6 is an under plan of the terminals for the glowers. Fig. 7 is a plan view of the rheostats and their terminals, and Fig. 8 is a diagrammatic view showing the circuit arrangement.

Referring to the drawings, A is a plate of asbestos upon the upper face of which is a mass of plaster-of-paris or similar material B, in which are embedded the lower ends of a plurality of rheostats B', similar to those in use in the ordinary Nernst lamp. A metallic rod A² extends through the asbestos plate and plaster-of-paris and supports a plate B², perforated to receive the upper ends of the rheostats to hold the same in place. The upper end of the rod A² carries a terminal block A³, having wire terminals of the ordinary form. A shell C, having handles c, is supported by the rod A² and the asbestos plate A to inclose the upper portion of the device.

On the lower face of the plate A is an inverted channel-shaped lava glower-support D, which supports a plurality of glowers d, such

as are in common use in the Nernst lamp. At the ends of this channel-shaped support are two single supports D', across which are stretched glowers d', running at right angles to the glowers d, and below the same and outside and parallel with the flanges of the support D is a third pair of glower-supports D², supporting glowers d², parallel with the glowers d, but lying below the spaces between them, as illustrated. Each of the glowers is arranged in series with one of the rheostats, the circuit arrangement being illustrated in Fig. 8. The terminals of the glowers and rheostats are clearly illustrated in Figs. 7 and 8, and no detailed description will be necessary. It will be seen that one terminal of each of the rheostats is connected to a ring E and that one terminal of each of the glowers is connected to one of three plates F, all of which are in electrical connection. The remaining terminals of the rheostats are connected to small binding-posts F', which are in turn connected to binding-posts F² on the lower face of the asbestos platform, (see Fig. 6,) to which are also connected the other terminals of the glowers, so that the current flows through both glowers and rheostats. The ring E and plates F are connected to the lead-wires E³ E⁴, as shown. Inasmuch as a great number of glowers are employed in close proximity to each other, the heat arising therefrom is so exceedingly intense that I have provided means for cooling the device, which, as here shown, consists of a tube O, extending back and forth through the platform. A cooling medium, such as water or air, is passed through the tube by any suitable means.

Below the plate A is supported a ring G, which carries a plurality of downwardly-projecting radial tubes G', preferably transparent and of violet color, which are filled with a mixture of radio-active substance, preferably barium sulfate, precipitated in the presence of uranium nitrate, and a phosphorescent substance, preferably zinc sulfid. Outside the plate A is a reflector H, adapted to concentrate the rays of light, and a metallic hood or shade I surrounds the entire structure and carries at its lower end a slide in which can

be inserted a sheet of suitably-colored glass or other transparent or translucent material *J* or a vessel of colored liquid to cut off the heat-rays as desired.

- 5 In operation the glowers of my improved device are heated with an alcohol flame or a Bunsen burner until they will conduct electricity, after which the device is operated as is the ordinary Nernst lamp. The heating-tubes 70
 10 of the Nernst lamp are omitted for two reasons. In the first place the cut-out device, which ordinarily accompanies the heating-tube, must be maintained in a single position in order to work properly, and consequently the device
 15 has not the necessary portability for therapeutic use. Furthermore, in order to get the desired intensity of light I arrange three series of glowers one above the other, and the heating-tubes would prevent any such system,
 20 because of the shadows which the heating-tubes of the lower glowers would cast. My present arrangement, it will be seen, gives the maximum of lighting effect with the minimum of shadows. This light is particularly desirable
 25 for therapeutic purposes because of its comparative freedom from red rays and the comparatively large number of violet and ultra-violet rays. The use of the radio-active and phosphorescent tubes greatly assists in the
 30 therapeutic action of the light. The light from the glowers is rich in chemical rays and increases the activity both of the phosphorescent material and the radio-active material.

It will be evident that as the device is constructed it can be placed in any desired position to treat any portion of the patient's anatomy.

The rays from my improved device are particularly desirable in their effects upon the 40 nerves, and they are entirely free from the burning effect of the X-rays and gama radium-rays. I find that the combined rays given off—that is, the light-rays, phosphorescent rays, and the rays from the radio-active 45 substance—form an especially desirable combination for my purpose. Another important advantage of this light is the fact that the light produced is of intense brilliancy and is devoid of any flickering or interruption in 50 the steadiness of the light. Such flickering has the effect of irritating the nerves of the system, and by avoiding this difficulty very beneficial results are obtained.

I realize that considerable variation is possible in the details of this construction without departing from the spirit of my invention, and I do not, therefore, intend to limit myself to the specific form herein shown and described.

60 I claim as new and desire to secure by Letters Patent—

1. In a device of the class described the combination with a suitable support, of a series of glowers carried thereby and suitable terminals for the glowers, the device being un-

provided with the heating-tubes usually employed, whereby portability of the device is obtained.

2. In a device of the class described, the combination with a suitable support, of a plurality of glowers in parallel planes, the glowers in the adjacent planes running at right angles to each other and the alternate planes alternating with respect to each other. 70

3. In a device of the class described, the combination with a series of glowers and suitable electrical connections therewith, of a plurality of tubes containing a radio-active substance surrounding the glowers. 75

4. In a device of the class described, the combination with a series of glowers and suitable electrical connections therewith, of a plurality of tubes containing a phosphorescent substance surrounding the glowers. 80

5. In a device of the class described, the combination with a series of glowers and suitable electrical connections therewith, of a plurality of tubes containing a mixture of radio-active and phosphorescent material surrounding the glowers. 85

6. In a device of the class described, the combination with a suitable light, of a plurality of tubes containing a radio-active substance surrounding the light. 90

7. In a device of the class described, the combination with a suitable light, of a plurality of tubes containing a phosphorescent substance surrounding the light. 95

8. In a device of the class described, the combination with a suitable light, of a plurality of tubes containing a mixture of radio-active and phosphorescent material surrounding the light. 100

9. In a device of the class described, the combination with a suitable light, of a plurality of transparent, violet-colored tubes, containing a radio-active substance surrounding the light. 105

10. In a device of the class described, the combination with a suitable light, of a plurality of transparent, violet-colored tubes containing a phosphorescent substance surrounding the light. 110

11. In a device of the class described, the combination with a suitable light, of a plurality of transparent, violet-colored tubes containing a mixture of radio-active and phosphorescent material surrounding the light. 115

12. In a device of the class described, the combination with a casing and an asbestos platform supported therein, a plurality of rheostats supported above said platform, a series of terminals connected therewith, a series of glowers supported upon the opposite side of the platform in electrical connection with said rheostats, a reflector surrounding said glowers and a hood inclosing the reflector and glowers. 120

13. In a device of the class described, the combination with a series of glowers, of a tubular ring surrounding the same, a series of 125

colored-glass tubes supported by said ring and a radio-active substance confined in said glass tubes and ring.

14. In a device of the class described, the combination with a suitable support, of a series of glowers supported thereby, a hood carried by said support and surrounding the glowers, a guide on said hood and a suitably-colored transparent plate supported in said guide.

15. In a device of the class described, the combination with a suitable support, of a plurality of glowers supported upon one side of said support, a plurality of rheostats in electrical communication with said glowers, and a cooling medium interposed between said glowers and rheostats.

16. In a device of the class described, the combination with a suitable support, of a plurality of glowers supported upon one side of said support, of a plurality of rheostats in electrical communication with said glowers, and a cooling-tube interposed between said glowers and rheostats and filled with a constantly-changing cooling fluid. 20 25

In witness whereof I have signed the above application for Letters Patent, at Chicago, in the county of Cook and State of Illinois, this 27th day of October, A. D. 1904.

ARTHUR H. POHL.
